SEMAUTOMATIC RIVETING DEVICE

John F. Cote, Dover, N. H.

Application July 3, 1944, Serial No. 543,376

5 Claims. (Cl. 78—48)

(Granted under the act of March 3, 1883, as
amended April 30, 1928; 370 O. G. 757)

1

This invention relates to a riveting device and has for an object to provide an improved riveting device preferably operated by a pneumatic hammer for applying hammer blows to the end of a rivet or to the ends of pair of rivets.

A further object of this invention is to provide a riveting device operable by a reciprocable end of a pneumatic or motor driven hammer.

A further object of this invention is to provide a riveting device having a manually operable means for simultaneously controlling the operation of the hammer and for rotating the rivet head and a second manually controllable clamp for holding the rivet to be headed.

Still further object of this invention is to provide a riveting device for heading a pair of rivet members and for simultaneously rotating a pair of rivet headers by a single manually controllable lever which lever is also connected to simultaneously control the operation of the hammer mechanism.

With the foregoing and other objects in view, this invention includes the construction, combinations, and arrangements of parts here and after set forth, disclosed, and claimed in the accompanying drawings, wherein

Fig. 1 is a side elevational view of the riveting device of this invention.

Fig. 2 is a front detailed view of the lower end of the riveting device.

Fig. 3 is a rear elevational view, partly in section.

Fig. 4 is a view on line 4—4 of the Fig. 3.

Fig. 5 is a view on line 5—5 of Fig. 1.

Fig. 6 is a view similar to Fig. 1 but partly in section.

Fig. 7 is a detailed view of a pneumatic hammer throttle valve control lever, and

Fig. 8 is a sectional view on line 8—8 of Fig. 6.

There is shown at 10 the riveting device of this invention. This riveting device as shown is particularly intended for heading a pair of rivets simultaneously but is obviously equally operable for heading single rivet. This riveting device 10 includes a foundation member 11 adapted to be secured by suitable bolts or other fastening members 12 to a floor or support 13.

Upstanding from the foundation 11 is a pair of spaced bosses 14 and 15. Extending upwardly through the front boss 14 through a suitable vertical shaftway 16 therein is a shaft 17 to which is eccentrically secured a cylindrical head 18. Mounted on a splined trackway 20 located on the top of boss 15 is a clamping member 21 provided with a shelf 22 on which the cylindrical head 18

rests, the shaft 17 extending upwardly through an elongated slot 23 in the clamp 21. A face plate 24 secured to the front of the clamp 21 extends above the shelf 22, the face plate 24 being spaced from the wall 25 at the rear end of the shelf 22 a distance just equal to the diameter of the cylindrical head 18.

Mounted on the upper end of the shaft 17 and spaced a distance from the cylindrical head 18 is a knob 29 from which extends a control rod 26. The shaft 17 is secured in position by means of a nut 27 on its bottom end located in a suitable recess 28 in the bottom of the foundation 11. A fixed clamping member 30 is secured by studs 31 to the rear boss 15, and is further secured thereto by means of the bolts 32 extending through a forwardly extending base plate 33 supported on a spacing block 34.

Threaded into the opposite sides of the base plate 33 are a pair of vertical rods 35 whose upper ends are threaded as 36 to receive pairs of nuts 37 for supporting an upper base plate 38 having a central aperture through which extends the barrel 40 of the pneumatic hammer 41. This pneumatic hammer 41 is of a conventional construction and is provided with the usual pressure supply pipe 42 and the usual throttle valve 43 which when depressed causes the hammer head 44 to reciprocate rapidly into and out of the barrel 40. The barrel 40 is normally held against movement in the upper base plate 38 by means of a pair of set screws 45 extending through the edges of the upper base plate as shown in Fig. 4. Mounted on the hammer head 44 is the hammer holder 46 which is provided with vertical perforations 47 so that it may slide freely up and down on the supporting rods 35.

Threaded through the lower base plate 33 are a pair of rivet header bushings 48 whose upper ends are formed into cup spring retainers 50 for receiving coiled springs 51 about the rivet headers 52, the rivet headers 52 being provided at their bottom ends with rivet header tools 53. The rivet headers 52 are threaded at their upper ends 54 for receiving spring basing washers 55 over which are mounted gears 56 secured in position by nuts 57 and lock washers 58. The gears 56 are spaced apart a distance from each other. Both gears 56, however, are in mesh with a central gear 60 of about twice the thickness of the gears 56.

This common gear 60 is adjustably journaled as at 61 on an angle support 62 adjustably secured by the studs 63 to the front edge of the lower base plate 33. It will be observed in Fig. 6

that the position of the gear 60 is adjustable by the means of its journal 61 extending through an elongated slot 64 in the angle support 62 and that similar elongated slots 65 are provided for the securing studs 63. Secured to the gear 60 by means of a stud 66 is a hinge plate 67 on which is horizontally pivoted as at 70 a hand feed control lever 71. It will be noted that the end of the hinge plate 66 is recessed to extend about the upper end of journal 61.

Extending through the hand feed control wheel 71 is a flexible member such as a chandelier chain 12 whose other end is held in the bifurcated end 73 of a lever 74 hinged at 75 to a hinged plate 76 mounted on the air hammer handle 77 by means of a nut 78. Secured to the bottom of the lever 74 is a foot 80 in such position as to abut against the top of the throttle barrel 43, and move it to the position 43' as shown in Fig. 6 when the lever 74 is depressed.

In operation, the riveting device of this invention provides means for riveting heads on a pair of studs, one of which is visible at 81 in Fig. 6, for securing the studs 81 through a plate 82.

The studs 81 are held in appropriate position between the fixed clamping member 30 and the movable member 21 by rotating the hand lever 26 so as to cause the eccentrically mounted head 18 to appropriately position the movable clamping member 21. The clamping members 21 and 39 may be vertically recessed as at 83 to insure the proper positioning of the studs 81. After the studs 81 are thus clamped by rotation of the lever 26, the plate 82 is placed thereover while hand feed lever 71 is in the position shown in Fig. 1.

The hand feed lever 71 is then depressed to the position shown in Fig. 6 causing the chain 72 through lever 74 and foot 80 to depress throttle barrel 43 and cause the hammer to operate. This causes a reciprocation of the hammer holder 46 and thus causes the rivet headers 52 to move their rivet header tool ends 53 in a riveting operation on the top ends of the studs 81. While holding the hand feed lever 71 depressed, it is simultaneously moved to and fro in a clockwise and counterclockwise motion. Due to the thickness of the gear 60, the gears 56 stay in constant mesh while reciprocating up and down and thus transmit the clockwise and counterclockwise motion of the hand feed lever 71 to the rivet headers 52, as a result of which, a suitable rivet head is formed on the upper ends of the studs 81 securingly fastening them to the plate 82.

The style of rivet headers 52 herein shown provide flat rivet heads 33 on the upper ends of the studs 81, but any suitable style of rivet headers may be substituted if other types of rivet heads are desired.

After the riveting operation is completed, the hand feed lever 71 is raised a slight amount permitting the throttle valve 43 to move to the off position and the handle 26 is rotated in the opposite direction to retract the clamping member 21 and release the studs 81 which are now riveted to the plate 82 and permit a new pair of studs and plate to replace them for a similar operation.

Other modifications and changes in the number and arrangement of the parts may be made by those skilled in the art without departing from the nature of this invention, within the scope of what is hereinafter claimed.

The invention described herein may be manufactured and used by or for the Government of the United States of America for governmental

purposes without the payment of any royalties thereon or therefor.

What is claimed is:

1. A riveting device for riveting studs to a member to be secured thereto, said device comprising means for temporarily clamping the stud, rivet header means, means for reciprocatably mounting said rivet header means in rivet heading position over the clamped studs, manually operative means for rotating said rivet header means to and fro, means for mounting a reciprocating hammer for reciprocating said header means, the reciprocating hammer having a control means, and means for connecting the hammer control means to said rivet header manually operative means for common control of both said means, said stud clamping means comprising a base, a fixed clamping member on said base, a movable clamping member, a splined trackway on said base on which said movable clamping member is slideably mounted, a shaftway formed in said base, said movable clamping member having an elongated slot over said shaftway, a shaft mounted through said shaftway and said elongated slot, a cylindrical head eccentrically mounted on said shaft, upstanding walls on said movable clamping member between which said eccentric head is located, and a lever secured to said shaft for rotating said eccentrically mounted head to thereby move said movable clamping member to and from clamping position.
2. A riveting device for riveting studs to a member to be secured thereto, said device comprising means for temporarily clamping the stud, rivet header means, means for reciprocatably mounting said rivet header means in rivet heading position over the clamped stud, manually operative means for rotating said rivet header means to and fro, means for mounting a reciprocating hammer for reciprocating said header means, the reciprocating hammer having a control means, and means for connecting the hammer control means to said rivet header manually operative means for common control of both said means, said means for reciprocably mounting said rivet header means comprising a base plate extending over said clamping means, a bushing extending through said base plate, said rivet header extending through said bushing, a coil spring about said rivet header based on said bushing, and means on said rivet header to base said coil spring thereagainst to thereby raise said rivet header each time it is depressed by said reciprocating hammer.
3. A riveting device for riveting studs to a member to be secured thereto, said device comprising means for temporarily clamping the stud, rivet header means, means for reciprocatably mounting said rivet header means in rivet heading position over the clamped stud, manually operative means for rotating said rivet header means to and fro, means for mounting a reciprocating hammer for reciprocating said header means, the reciprocating hammer having a control means, and means for connecting the hammer control means to said rivet header manually operative means for common control of both said means, said means for mounting the reciprocating hammer for reciprocating said header means comprising an apertured base plate through which the barrel of the hammer is extended, means fastening the barrel to said apertured base plate, supporting rods on which said apertured plate is mounted, and a hammer holder mounted on the hammer, said hammer

holder being provided with guide holes through which said supporting rods extend.

4. A riveting device for riveting studs to a member to be secured thereto, said device comprising means for temporarily clamping the stud, rivet header means, means for reciprocatably mounting said rivet header means in rivet heading position over the clamped stud, manually operative means for rotating said rivet header means to and fro, means for mounting a reciprocating hammer for reciprocating said header means, the reciprocating hammer having a control means, and means for connecting the hammer control means to said rivet header manually operative means for common control of both said means, said manually operative means for rotating said rivet header means to and fro comprising a gear secured about said rivet header means, a second gear of substantially greater thickness than said first mentioned gear, means for adjustably mounting said second gear, both vertically and horizontally, with relation to said first gear, to properly mesh said gears together, said greater thickness of said second gear enabling said first gear to remain in mesh therewith while it is reciprocated with said rivet header means, a hand lever, and means for securing said lever radially of said second gear.

5. A riveting device for riveting studs to a member to be secured thereto, said device comprising means for temporarily clamping the stud, rivet header means, means for reciprocatably mounting said rivet header means in rivet heading position over the clamped stud, manually operative means for rotating said rivet header means to and fro, means for mounting a reciprocating hammer for reciprocating said header means, the reciprocating hammer having a control means, and means for connecting the hammer control means to said rivet header man- 40

ually operative means for common control of both said means, said manually operative means for rotating said rivet header means to and fro comprising a gear secured about said rivet header means, a second gear of substantially greater thickness than said first mentioned gear, means for adjustably mounting said second gear, both vertically and horizontally, with relation to said first gear, to properly mesh said gears together, said greater thickness of said second gear enabling said first gear to remain in mesh therewith while it is reciprocated with said rivet header means, a hand lever, and means for securing said lever radially of said second gear, 10 said reciprocating hammer control means comprising a depressible throttle valve, said common control means comprising a lever hingedly mounted on said reciprocating hammer, a foot on said last-mentioned lever adapted to abut said 15 throttle valve to depress the same, a flexible member connecting said last-mentioned lever to said afore-mentioned hand lever, said means for radially securing said afore-mentioned hand lever to second gear comprising a hinge plate 20 and a pivotal connection, transverse to the gear radius, between said hand lever and said hinge plate.
